UNITED STATES PATENT OFFICE.

ALFRED F. MASURY, OF NEW YORK, N. Y., ASSIGNOR TO INTERNATIONAL MOTOR COMPANY, OF NEW YORK, N. Y., A CORPORATION OF DELAWARE.

DESIGN FOR AN ENGINE-HOOD FOR A MOTOR-VEHICLE.

53,373.

Specification for Design.

Patented May 27, 1919,

Application filed December 21, 1918. Serial No. 267,861. Term of patent 14 years.

To all whom it may concern:

Be it known that I, ALFRED F. MASURY, a citizen of the United States, residing in the borough of Manhattan, of the city of New York, in the State of New York, have invented a new, original, and ornamental Design for Engine-Hoods for Motor-Vehicles, of which the following is a specification, reference being had to the accompanying drawing, in which—

Figure 1 is a view in perspective of an engine hood for motor vehicles which shows the design, and

Fig. 2 is a top view thereof.

I claim—

The ornamental design for an engine hood for a motor vehicle, as shown.

This specification signed this 19th day of December, A. D. 1918.

ALFRED F. MASURY.
